Patented Jan. 7, 1919.

UNITED STATES PATENT OFFICE.

THOMAS CARTER, OF ENGLEWOOD, NEW JERSEY, ASSIGNOR TO THOMAS CARTER & SONS, INC., A CORPORATION OF NEW YORK.

DESIGN FOR A CUT-OUT CARD.

52,839.

Specification for Design.

Patented Jan. 7, 1919.

Application filed April 12, 1918. Serial No. 228,273. Term of patent 7 years.

To all whom it may concern:

Be it known that I, THOMAS CARTER, a citizen of the United States, residing at Dwight Place, in the city of Englewood, Bergen county, State of New Jersey, have invented a new, original, and ornamental Design for a Cut-Out Card, of which the following is a specification, reference being had to the accompanying drawing, forming a part hereof.

The figure is a plan view of the cut-out card showing my new design.

I claim:

The ornamental design for a cut-out card, as shown.

THOMAS CARTER.
